H. C. SCHAPER

FULCRUM CONNECTION

Filed April 13, 1923

UNITED STATES PATENT OFFICE.

HARRY C. SCHAPER, OF ST. LOUIS, MISSOURI, ASSIGNOR TO THE WEIGHT-O-GRAPH COMPANY, OF ST. LOUIS, MISSOURI, A CORPORATION OF MISSOURI.

FULCRUM CONNECTION.

Original application filed October 13, 1921, Serial No. 507,492. Divided and this application filed April 13, 1923. Serial No. 631,901.

My invention relates generally to new and useful improvements in fulcrum connections and more particularly to double-knife edge pivot connections between scale levers.

5 The present application is a division of an application for patent on weight indicating scales filed by me October 13, 1921, Serial Number 507,492.

The objects of the invention are to provide 10 simple and highly efficient pivot connections for the interengaged load receiving levers whereby friction is reduced to minimum without impairing the load responsiveness of the levers.

15 Further objects of the invention are to provide a double-knife edge pivot member for the load actuated levers and to provide means for retaining said pivot member in operative relation with one of said levers.

20 With these and other objects in view my invention consists in certain novel features of construction and arrangement of parts hereinafter more fully described and claimed, and illustrated in the accompanying drawings, in which—

25 Figure 1 is a longitudinal cross section through the base of a scale and showing the weight receiving platform arranged thereon.

30 Figure 2 is a fragmental plan view of the load-actuated levers and showing the interengagement thereof.

Figure 3 is a vertical cross section taken on line 3—3 of Figure 2.

35 Figure 4 is a vertical cross section taken on line 4—4 of Figure 3.

Figure 5 is an end elevation of the pivot member and one of the bearing blocks and showing means for retaining said pivot member in operative relation with said block.

40 Figure 6 is a perspective detail view of one of the retaining plates.

Referring by numerals to the accompanying drawings, 10 indicates a box-shaped base 45 which houses the load receiving lever system of a scale. Projecting inwardly from the side walls of said base are cylindrical portions 11 in which are mounted bearings 12. The upper ends of these bearings carry bearing blocks 14 having upwardly presented V-shaped grooves in which are arranged the knife edges of pivot members 15. These pivot members are fixed in the ends of a pair of spaced parallel bars 16 and 17, transversely disposed in the base 10. A bar 16

which occupies the forward end of the base 10 has inwardly projecting arms 16^a to the extremities of which are fixed upwardly presented knife-edge pivot members 18. The bar 17 which is located toward the rear 60 of the base 10 has inwardly projecting arms 17^a and the extremities thereof are provided with upwardly presented pivot members similar to the members 18.

A bearing block 19 carried by the upper 65 end of a loop 20 is provided with a downwardly presented V-shaped groove which is designed to be engaged by the knife edge of the pivot member 18 and support the loops 20 on the arms 16^a and 17^a. These loops 70 straddle the ends of said arms, and the lower ends of said loops are designed to receive the hooked upper ends of short rods 21. The lower ends of said rods have adjustably mounted thereon semi-spherical members 22, 75 which are received in bearings formed in the undersides of the stirrups 24, and support the same in position. The upper ends of the stirrups 24 are secured to, or formed integral with a spider 25 which extends upwardly through a suitable opening formed in the upper end of the base 10. This spider is provided at its corners, and preferably in vertical alignment with pivot connections 19, 20, and with bosses 26 having suitable 80 sockets for receiving the pins 27 and a platform 28. Thus the platform 28 which is arranged above the spider 25 and is spaced from and surrounds the upper end of the base 10, is supported in position and suspended from the arms 16^a and 17^a by the loops 20 and the stirrups 24.

A lever 29 is fixed at its forward end to the bar 16 and extends rearwardly in the base 10 and its extreme rear end carries a 95 nose portion 30, which is designed to be engaged by a loop 31 fixed to the lower end of a steelyard rod 32 the upper end of which is connected to suitable weight indicating mechanism. A lever 34 extends inwardly 100 and forwardly from bar 17 and is preferably bifurcated at 34^a to clear the lever 29, and the forward end of said lever extends upwardly through a slot 35 formed in the lever 29, and is provided with a horizontally disposed portion 36 which occupies a position 105 above the lever 29, as shown in Figures 1 and 3. This horizontal portion has arranged therein a bearing block 37 having a downwardly presented V-shaped groove 38, 110

which is adapted to engage the upwardly presented knife edge of a pivot member 39.

A bearing block 40, having an upwardly presented V-shaped groove 41, is carried by the lever 29 and extends across the slot 35 and receives the downwardly presented edge of the member 39. Thus the member 39 forms a double-knife edge pivot connection between the levers 29 and 34, and this connection is flexible and self-centering and maintains the interengaged levers in their proper operative relation.

The bearing block 37 is preferably held in position by a pin 42 which passes through said block and is seated in the horizontal portion 36. This pin is centrally located in said portion and permits slight rocking movement of block 37 whereby the latter can automatically adjust itself with respect to the block 40 and the member 39. In order to prevent displacement of the member 39, during the assembling of the device, said member is preferably retained in operative relation with the bearing block 37 by means of retaining plates 44, which are secured to the block 37 by suitable fastening devices 45 and are provided at their lower ends with inwardly presented lateral projections 46. The member 39 is provided at its ends with outwardly projecting portions 47 which, when the member 39 is seated in the blocks 37 and 40, are spaced from the projections 46 so that the latter cannot interfere with member 39. However, when the lever 34 or the blocks 37 are moved or disengaged from the lever 29 the projections 46 of the plates 44 will engage the fingers 47 and retain the member 39 in its operative relation with the block 37, thereby preventing displacement or loss of said member.

I claim:

1. An operative connection for a system of interengaged levers comprising a pair of opposed bearing blocks, and a double-knife edge member interposed between said blocks and in operative engagement therewith.
2. A pivot connection for a system of interengaged levers comprising a pair of opposed grooved bearing blocks, and a double-knife edge member interposed between said blocks and having bearings therein for transmitting the load from one bearing block to the other.
3. An operative connection for a system of interengaged levers comprising a pair of opposed bearing blocks, a double-knife edge member adapted to be interposed between said blocks and have operative engagement therewith, and means for retaining said double-knife edge member in operative relation with one of said bearing blocks.
4. A fulcrum connection for a pair of load receiving levers comprising a pair of opposed bearing blocks adapted to be arranged

in the respective levers, and a double-knife edge member engaging said blocks and operatively interengaging said levers.

5. A fulcrum connection for a pair of load receiving levers comprising a pair of opposed bearing blocks adapted to be arranged in the respective levers, and a double-knife edge member engaging said blocks and operatively interengaging said levers, and means for retaining said double-knife edge member in operative relation with one of said levers.

6. A pivot connection for a system of interengaged levers comprising a pair of opposed grooved bearing blocks, a double knife-edge member having bearings in said blocks, and retaining plates fixed to one of said blocks and having means normally disengaged from said member and adapted to engage said member and retain it in operative relation with the respective block when the latter occupies a displaced position.

7. In a device of the class described, the combination with a pair of cooperating levers, of a double-knife edge fulcrum member operatively interengaging said levers, and means for retaining said fulcrum member in operative relation with one of said levers.

8. In a device of the class described the combination of a pair of levers, a V-shape grooved bearing block fixed to one of said levers, another V-shape grooved bearing block adjustably arranged in the other one of said levers in operative relation with the first-mentioned bearing block, and a double-knife edge member engaging said bearing blocks and forming an interengaging fulcrum connection for said levers.

9. In a weighing scale, the combination with a beam lever, of a lever having a knife-edge bearing at one end and an operative connection with said beam lever at its other end, a lever oppositely disposed to the first mentioned lever and having a knife-edge bearing at its remote end, the other end being arranged above the first lever, and a double knife-edge member having bearing in said levers at a point equidistant from the fulcrums of said levers.

10. In a weighing scale, the combination with a beam lever, of a lever having a knife-edge pivot at one end, and an operative connection with said beam lever at its other end, a lever oppositely disposed to the first mentioned lever and having a knife-edge pivot at the remote end, a double knife-edge pivot member having cooperative bearings in said levers, the pivots of said cooperative levers and the operative connection between one of said levers and said beam lever being arranged on the same horizontal plane and said double edge pivot member having its bearing edges arranged equidistant above and below said horizontal plane.

11. In a weighing scale, the combination with a beam lever, of a lever having a knife-edge pivot at one end and an operative connection with said beam lever at its other end, a lever oppositely disposed to and parallel with the first mentioned lever and having a knife-edge pivot at its remote end, the other end being arranged above the first lever, a double knife-edge pivot member having bearings in said levers at a point 10 equidistant from the pivots of said levers, and means for retaining said double knife-edge pivot member in assembled relation with one of said levers.

In testimony whereof I hereunto affix my 15 signature this 30th day of March, 1923.

HARRY C. SCHAPER.
